LAMP CONSTRUCTION.

Application filed September 3, 1925. Serial No. 54,314.

This invention relates to improvements in lamp constructions.

The primary object of this invention is the provision of an improved type of lamp construction, preferably adapted for use as a signal or marker lamp for railway use, embodying means for detachably and electrically connecting the lamp globe of the improved marker lamp.

10 A further object of this invention is the provision of an improved marker lamp, including a novel type of one piece casing so constructed as to prevent snow, ice, and other foreign deposits thereon.

15 A further object of this invention is the provision of a very compact and light weight marker lamp for trains, embodying a novel detachable connection for the lamp unit thereof.

20 A further object of this invention is the provision of a marker lamp adapted for such use as is set forth in our copending application Serial No. 2,961, filed January 16, 1925, and of which copending application the present application is in part a division.

Further objects and advantages of this invention will be apparent during the course of the following detailed description.

In the accompanying drawing, forming a part of this specification, and wherein similar reference characters designate corresponding parts throughout the several views.

Figure 1 is a vertical cross sectional view taken longitudinally of the improved lamp, showing improved features of the same, particularly showing the lamp unit supporting means in side elevation.

Figure 2 is a fragmentary detail sectional view taken through the base portion of the lamp, showing novel features thereof.

Figures 3 and 4 are transverse sectional views taken substantially on their respective lines in Figure 1 of the drawing.

In the drawing, wherein for the purpose of illustration, is shown only a preferred embodiment of the improved lamp construction, the letter A may generally designate the improved marker lamp which may include a one piece casing 25, lenses 26 sup-

ported thereby; supporting and mounting 50 means 27 of the character set forth in our copending application above referred to; and a detachable lamp unit supporting means 28.

The casing 25 of the improved electrically 55 operated marker lamp A is formed of either pressed or cast aluminum, although other metal or materials may be used. Aluminum is chiefly desirable because of its lightness in weight and the ability to readily cast the 60 casing. The casing includes a top wall 30, and the four side walls 31, 32, 33 and 34, which are arranged in right angled relation with respect to each other and with respect to the top wall 30. All of the top 65 and side walls are formed integral, and all sharp corners at the juncture of said walls are eliminated, and in lieu of sharp corners convex corners 36 struck from relatively 70 large radii are provided, so that the casing 70 provides but few sharp obstructions for the collection of snow, sleet, dirt, or other foreign media. Each of the side walls 31 to 34 inclusive is provided with a substantially centrally arranged circular opening 37, for 75 detachably receiving therein the standard tested concavo-convex lens 26, with the convex surface of the lens projecting exteriorly of the opening and outer side surface of its respective wall of the casing 25. Each of 80 these lenses 26 is provided with a flange portion 38 overlying the interior surface of its respective wall about the opening 37, and in connection with each lens 26 a clamping 85 ring 40 is provided, adapted to overlie this flange 38 of each lens; the ring 40 being provided with a plurality of laterally extending attaching ears 41, being apertured, for receiving countersunk headed screws or bolts 42 therethrough, by means of which 90 each ring 40 may be clamped to its adjacent casing wall, for retaining its respective lens 26 in position. If desired, flexible washers, of fiber, or the like, may be provided between the rings 40 and the lens 26, 95 and between the lens flange 38 and adjacent wall which it abuts. The compartment 45 provided in the lamp casing 25 is open

downwardly through the casing 25, as a means of attaching the lamp unit supporting means 28 in the compartment 45, and as will be subsequently described.

To facilitate carriage of the marker lamp, a bail 47 is pivotally supported by suitable attaching ears 48 secured at opposite sides 31 and 33 of the casing 25; said bail 47 normally extending upwardly of the casing top 10 wall 30.

Referring to the construction 27 in so far as the same relates to the application of the same to a signal lamp, for the purposes of this invention it includes a circular collar 15 or hollow cylindrical member 50 within the lower open end of the casing 25, the same being of sufficient diameter to contact the inner surfaces of the side walls 31 to 34 inclusive, and therein the said collar 50 is riveted, as by rivets 51 and 51^a to each of said side walls, so that the lower portion of the collar 50 extends below the lower edge 52 of the casing 25. This collar 50 is provided with a passageway 54 therethrough 20 communicating with the compartment 45. At its lower end the casing 25 has secured exteriorly thereof the polygonal shaped band 56, which conforms to the shape of the side walls of the casing 25, and is secured to 25 the casing 25 by means of the rivets 51^a above mentioned, so that the lower edge 57 of said band 56 lies flush with the lower edge 52 of the casing 25. Secured to the lower outer surface of that portion of the collar 50 which extends below the casing edge 52 is 30 an annular band 60, which may be constructed of aluminum or like material, similar to the aluminum collar 50 and aluminum band 56; this band 60 being secured to the outer surface of the said lower portion of the collar 50 by means of detachable bolts 61, so that the upper edge 62 of said band 60 is spaced from the lower flush edges 52 and 57 above mentioned, to provide the annular 35 groove 65 between the edges 52 and 62, which is adapted to rotatably receive the circular body portion 66 of the lamp supporting bracket 67.

The bracket 67 is preferably constructed 40 of wrought iron or analogous durable material, and the circular portion 66 is of just sufficient width that its upper and lower edges contact in sliding abutment against the flush edges 52 and 57 and the edge 62 of 45 the band 60.

Referring to the detachable lamp member supporting construction 28, the same includes an aluminum base 85 of a novel construction, which is adapted to detachably 50 fit within the passageway 54 of the casing attaching collar 50. This base 85 includes the circular or disc shaped body 87, having an annularly depending attaching flange 88 which upwardly from the lower marginal 55 edge 89 thereof is provided with bayonet

slots 90 of any approved formation and number. Three of these bayonet slots 90 are preferably provided, and each of said slots includes an entrance way 91, entering the flange 88 at right angles to the edge 89; 70 a diagonal or inclined intermediate portion 92; and an upper notch portion 93 disposed at right angles to the lower edge 89 of said flange 88. A plurality of radially extending steel pins 95, preferably three in number, are detachably threaded in the collar 50, and project into the passageway 54 as a means of supporting the base 85 incident to the reception of the projecting ends of said pins 95 in the bayonet slots 90. The pins 80 95 are preferably provided 120° apart, as are also the bayonet slots 90. Between adjacent bayonet slots the base 85 is preferably provided with vertical passageways 100 extending upwardly entirely along the attaching flange 88 and through the edge portion of the top wall or disc 87; said passageways 100 being provided as a means of elevating the base 85 thru the passageway 54 of the collar 50 past the projecting ends of the pins 95 until the base 85 is elevated so that the said base may be turned slightly to permit the entrance of the projecting ends of the pins 95 into the bayonet slots 90.

Upwardly upon the top wall or disc 87 of the base 85 it is preferred to fix a porcelain socket 101 of any approved character, which detachably receives therein the metal plug end 102 of an incandescent bulb 103. Flexible wires 104 and 105 preferably extend downwardly through the base wall 87, through the collar passageway 54, and are received in flexible armored cable 106; said flexible armored cable 106 preferably leading to any suitable electrical supply source. 100

The flange 88 of the base 85 is also provided with means to grasp the same and facilitate the rotation of the unit 28 to permit its attachment or detachment with respect to the lamp housing, and this means 110 for so grasping the unit 28 preferably comprises three radially extending pins 110, connected at their ends in the flange 88 and extending radially thereof and at their proximate ends being connected in a connecting hub 111 axially disposed in the passageway 54. The hub 111 is a disc of aluminum, and is provided with a central opening 111^a, through which the armored cable 106 extends, to definitely locate this armored cable and prevent the breaking of the wires at the lamp base in the case of a sudden pull upon the cable. As the hub 111 is spaced from the interior surface of the flange 88 the intermediate portions of the pins 110 are exposed so that a person reaching upwardly through the passageway 54 of the collar 50 may readily grasp the same with his fingers to rotate the unit 28 115 for the purpose of effecting attachment or 120 detachment. 125

detachment with respect to the casing 25. These pins 110 and hub 111 really constitute a hand grasping spider attached to the base 85 to facilitate its removal or attachment, or to perform a rotation of the entire casing with respect to its bracket, for changing a signal. It is to be noted that the pins 110 are spaced a considerable distance below the top wall 87, to permit the operator to insert the tips of his fingers between the pins and the wall 27, to obtain an efficient grasp to prevent the attachment or detachment of the lamp supporting unit. From the foregoing description of this invention it will be apparent that a novel type of marker lamp has been provided, in connection with railway signalling as set forth in our co-pending application above referred to. The flexible wires and armored cable entering through the bottom passageway of the lamp casing and the collar 50 are positioned so that they connect to the lamp bulb and base of the lamp bulb protected from accumulations of snow, ice, or other foreign material, and the opening in the casing permits the facile attachment and detachment of unit construction 28 with respect to the casing 25. The entrance of the unit 28 to the casing is effected through the bottom of the casing and through the passageway 54 of the collar 50; the vertical passageways 100 being aligning with the inwardly projecting ends of the pins 95, and the base 85 moved upwardly by sliding the base with the passageways 100 along the pins 95 until the base 85 is positioned above the pins 95. By slight rotation of the base 85 the bayonet slots may be positioned to engage over the inwardly projecting ends of the pins 95 to secure the attachment of the base 85 and the unit 28 in the casing, in the relation illustrated in Figure 2 of the drawings. To effect such attachment or detachment of the casing the spider carried by the base is of course important, and the entire casing 25 may be rotated by means of this spider, to change the positioning of the casing 25 in the bracket body 66. Thus, a compact, light in weight, and economically constructed and efficient operating marker lamp has been provided, which embodies features particularly well adapted to render the use of an electric marker lamp practical for use of signalling on train coaches. The facility with which the bulb may be renewed and repairs made is important, since with the oil burning type of lamp the entire removal of the lamp is necessitated, whereas with the improved type of electrically operated marker lamp A, it is only necessary to detach the lamp carrying unit 28.

Various changes in the shape, size, and arrangement of parts may be made to the

form of invention herein shown and described, without departing from the spirit of this invention or the scope of the claims.

We claim:

1. In a signal of the class described a casing providing a compartment therein opening through a passageway downwardly in said casing, lenses laterally supported by the casing, pins fixed with the casing extending radially into said passageway, a substantially circular base including vertical passageways along the marginal portions thereof by means of which the base may be extended into the passageway of the casing and upwardly past said pins, said base at the lower edge thereof having upwardly extending bayonet slots for detachably receiving said pins upon rotational movement of the base in the passageway of said casing, and a lamp supported upwardly by said base in the compartment of the casing.

2. In a signal of the class described a casing providing a compartment therein opening through a passageway downwardly in said casing, lenses laterally supported by the casing, pins fixed with the casing extending radially into said passageway, a substantially circular base including vertical passageways along the marginal portions thereof by means of which the base may be extended into the passageway of the casing and upwardly past said pins, said base at the lower edge thereof having upwardly extending bayonet slots for detachably receiving said pins upon rotational movement of the base in the passageway of said casing, a lamp supported upwardly by said base in the compartment of the casing, and a hand engaging spider carried by the base in downwardly facing relation to the passageway of said casing whereby an operator may reach upwardly through said passageway thru the bottom of the casing to engage said spider.

3. In a signal lamp the combination of a casing including side walls having openings therein and lenses supported in said openings, said casing having a compartment opening through a passageway at the bottom of the casing, pins radially extending into the passageway below the lens supporting openings of said casing, a base including a top wall and an annular attaching flange depending from the top wall, said top wall and annular attaching flange having vertical ways therealong so that the base may be inserted into the passageway from the bottom of the casing and slipped upwardly past said pins with the pins projecting through the ways, said attaching flange having bayonet slots upwardly from the lower edge thereof between said ways for detachably receiving the projecting pins upon lowered movement of the base within said casing for stably mounting the base in said

casing, and a lamp unit supported by the top wall of the base within the compartment of said casing.

4. In a signal lamp the combination of 5 a casing including side walls having openings therein and lenses supported in said openings, said casing having a compartment opening through a passageway at the bottom of the casing, pins radially extending 10 into the passageway below the lens supporting openings of said casing, a base including a top wall and an annular attaching flange depending from the top wall, said top wall and annular attaching flange 15 having vertical ways therealong so that the base may be inserted into the passageway from the bottom of the casing and slipped upwardly past said pins with the pins projecting into the ways, said attaching 20 flange having bayonet slots upwardly from the lower edge thereof between said ways for detachably receiving the projecting pins upon lowered movement of the base within 25 said casing for stably mounting the base in said casing, a lamp unit supported by the top wall of the base within the compartment of said casing, and radially extending pins carried by the attaching flange of said casing below the top wall of the base extending 30 into the passageway whereby an operator may reach upwardly through the passageway of the casing and engage said last mentioned pins to effect attachment and detachment of the base with respect to the 35 casing.

5. As an article of manufacture a lamp supporting unit for signal lamps comprising a base including a supporting wall having an annular depending attaching flange 40 with bayonet slots upwardly extending from the lower edge thereof, lamp means supported by the supporting wall of said base at the opposite side thereof from said attaching flange, and a hand engaging spider 45 supported by said attaching flange in a plane in a spaced relation below said lamp supporting wall.

6. As an article of manufacture a lamp supporting unit for signal lamps comprising a base including a supporting top wall having an annular depending attaching flange with bayonet slots upwardly extending from the lower edge thereof, lamp means supported by the top wall of said base at the opposite side thereof from said attaching flange, said attaching flange and wall having ways vertically therealong between 50 said bayonet slots.

7. As an article of manufacture a lamp 60 supporting unit for signal lanterns comprising a metal base including a supporting wall having a depending attaching flange with bayonet slots extending upwardly from the lower edge of said attaching flange, a socket member carried upwardly by said support-

ing wall, a lamp detachably connected in said socket member, said attaching flange having vertical ways therealong between said bayonet slots, and a hand engaging spider carried by the attaching flange below 70 said supporting wall and at the opposite side thereof from said socket.

8. In a lamp construction of the class described a casing providing a compartment therein opening through a passageway downwardly in said casing, lenses laterally supported by the casing, pins carried by the casing extending radially into said passageway, a base including bayonet slots for detachably receiving the pins which extend 75 into said passageway, said base including a top wall, a lamp supported on the top wall, and finger grasping pins carried by the base in spaced relation below the top wall thereof, the space between the last mentioned pins and the top wall being sufficient 80 to permit the insertion of a person's fingers in order to facilitate attachment or detachment of the base with respect to the casing.

9. In a signal lamp the combination of a casing providing a compartment therein and a passageway opening downwardly through the casing, lenses supported by the casing, a base detachably carried by said casing in 95 the passageway thereof, a lamp bulb upon the upper portion of said base, an electrical conducting cable leading upwardly from below the casing through the passageway thereof and through the base to said lamp bulb, and finger grasping means carried by the lower part of the base which a person can grasp by inserting a hand upwardly into the passageway of said base, said finger grasping means including a central supporting disc having an aperture through 100 which said cable loosely extends.

10. As an article of manufacture a lamp supporting unit for signal lanterns comprising a base including a supporting wall having a depending attaching flange, a lamp detachably connected above said supporting wall, and a hand spider carried below the supporting wall by said attaching flange including substantially radially extending pins 110 connected with a central disc shaped hub having a central aperture therethrough.

11. In a signal lamp of the class described a casing having a compartment therein and an opening in the lower end thereof to said compartment, said casing having lateral lenses thereon, pins supported rigidly with the casing extending in projecting relation into the lower end opening of the casing, 120 a base including a top wall and a depending flange, lamp means supported on the top wall, said base having passageways substantially vertically therealong extending from the lower edge of the flange thereof upwardly thru the top wall thereof so that 125

the base may be inserted in the lower end opening of the casing to be received entirely within the casing, the pins of the casing opening being received in said slots to permit the base to be elevated above said pins, said flange of the base inwardly of the lower edge thereof having recesses between the

slots of the base whereby to receive the projecting pins of said casing upon slight rotation of the base when disposed in the casing above said pins, whereby to support the base entirely within the opening of said casing.

WILLIAM B. BARRY, JR.
EDWARD G. MYERS.
